UNITED STATES PATENT OFFICE.

ALBERT B. CRESSLER, LUDWIG B. NEES, AND HARRY B. BAUMBACH, OF MIDDLETOWN, PENNSYLVANIA.

SASH-WEIGHT.

1,344,176.

Specification of Letters Patent. Patented June 22, 1920.

Application filed December 17, 1919. Serial No. 345,581.

To all whom it may concern:

Be it known that we, ALBERT B. CRESSLER, LUDWIG B. NEES, and HARRY B. BAUMBACH, citizens of the United States, residing at 5 Middletown, in the county of Dauphin and State of Pennsylvania, have invented certain new and useful Improvements in Sash-Weights, of which the following is a specification.

10 This invention relates to improvements in the balancing weights for window sashes. The old form of sash weight which is now in general use and which consists of an integral solid cast body having a perforated 15 ear at one end presents several disadvantages in its use. Inasmuch as window sashes vary greatly in weight, it is often a difficult matter to procure a sash weight of precisely the weight required to serve its purpose in balancing the particular sash to be fitted and under these conditions it is customary to select a weight heavier than the one required and then break off a piece of the same so as to suitably reduce its weight. 20 This, however, involves the expenditure of time and labor and there is always the liability of breaking off too large a portion of the weight. Furthermore, dealers in supplies of this kind are required to carry in 25 stock various sizes of the weights which is another undesirable feature. In the use of the ordinary weight, furthermore, the sash cord end is threaded through the opening in the ear of the weight and then knotted but as 30 a result of this method of attachment, the weight is not perpendicularly suspended as regards its long axis but is suspended in a more or less tilted position so that it is liable to run unevenly in the window frame 35 and become hung and, furthermore, the sash cord is liable to become untied. In either event it is necessary to open the window frame to remedy the trouble and this also involves the expenditure of time and labor. 40 In consideration of the disadvantages presented by the ordinary form of sash weight as briefly pointed out above, the present invention has as one of its primary objects to provide a weight so constructed that 45 its mass may be readily increased or diminished in a simple manner and without destroying or damaging any portion of the weight.

Another object of the invention is to provide a sash weight so constructed that the

same may be manufactured in a single standard size or at most in a minimum number of different sizes thus reducing the number and variety of the articles which a dealer is required to keep in stock, the 60 weight being capable of being readily filled to a greater or less extent with a suitable weighting material until it possesses the required mass depending, of course, upon the weight of the sash to be balanced.

65

A further object of the invention is to so construct the weight that the sash cord may be readily and conveniently connected therewith in a manner to perpendicularly suspend the weight so that the same will travel 70 freely in the stiles of the window frame.

The invention also has as one of its objects to so construct the attaching member of the weight that, with equal facility, a sash cord, chain, or tape may be connected 75 therewith.

A further object of the invention is to so construct the connecting member for the sash weight that where the weight is to be employed in connection with a sash cord, 80 the knot tied in the end of the cord will be securely housed within the attaching member and weight so that it cannot become loose and in which position it will be protected from contact with parts of the sash 85 which contact, in the use of the ordinary type of weight frequently results in the knot being untied or worn through.

In the accompanying drawings:

Figure 1 is a perspective view of the sash 90 weight embodying the present invention, the same being illustrated as suspended from a sash cord;

Fig. 2 is a vertical longitudinal sectional view through the weight shown in Fig. 1; 95

Fig. 3 is a transverse sectional view taken on the line 3-3 of Fig. 2 and looking in the direction of the arrows;

Fig. 4 is a view similar to Fig. 2 but illustrating the manner in which a sash chain 100 may be connected with the weight;

Fig. 5 is a similar view illustrating the manner in which a sash tape may be connected with the weight.

The weight embodying the present invention is indicated in general by the numeral 1 and the same comprises a hollow cylindrical body 2 which is of metal or other suitable material and which is interiorly threaded at its upper and lower ends as indicated respec- 105 110

tively by the numerals 3 and 4. The lower end of the body is closed by means of a plug 5 threaded into the said end and provided with a polygonal boss 6 for the application 5 of a wrench or other tool for the purpose of fitting into place or removing the said plug.

The upper end of the body 2 is closed by means of a combined plug and attaching member which is indicated by the numeral 10 7 and the same comprises a plug body which is threaded into the upper end of the said body 2 and is formed exteriorly upon its top with a boss 8 which is preferably polygonal for the application of a wrench or other tool 15 as in the case of the plug 5. This boss and the said top of the plug 7 are formed with an opening 9 preferably cylindrical and extending in line with the axis of the said plug 7 and body 2. The boss 8 is formed also in 20 diametrically opposite sides with perforations 10 which are in alinement and communicate with the opening 9.

In the use of the weight, the same is filled or partly filled with any suitable weighting 25 material 11 such for example as metal disks, punch slugs, metal turnings or cuttings, dry sand, iron ore, or in fact any material a quantity of which may be contained within the body and which will in conjunction with 30 the weight of the body, provide sufficient mass to properly balance the sash to be hung. In Figs. 1 and 2 of the drawings the weight is employed in connection with a sash cord of the ordinary type which is indicated by 35 the numeral 12 and the lower end of this cord is fitted downwardly through the opening 9 and is tied in a knot 13, the cord being then drawn through the opening so that the knot will seat and be housed within the 40 cavity of the plug 7, the plug being hollow as indicated by the numeral 14, for this purpose. The cord having been connected with the plug 7 in the manner stated and the body of the weight having been supplied 45 with a suitable mass of the filling material or metal disks 11, the plug is threaded into the upper end of the body and the weight is then ready to perform its functions. Of course, if the weight is found to be too massive, either the plug 7 or the plug 5 may be removed and a greater or less number of disks or quantity of the filling material may

be discharged from the weight, or, if the weight is found to be too light after its ends have been closed, the plug in either end may 55 be removed and more of the disks or filling material may be introduced.

In the form of the invention shown in Fig. 3 of the drawings, the weight is employed in connection with a sash chain which 60 is indicated by the numeral 15, the lowermost or terminal link of this chain being fitted within the opening 9, and a pin 16 being driven through the perforations 10 and through the eye of the link so as to connect 65 the link with the plug 7.

In Fig. 4 of the drawings the numeral 17 indicates a metal tape such as is sometimes employed in hanging sashes and the end of 70 this tape is formed with a perforation 18 and is fitted into the opening 9 after which a pin 19 corresponding to the pin 16, is driven through the perforations 10 and through the opening 18 in the said tape so as to connect the tape with the weight. 75

The interior walls of the opening 9 at the upper and lower ends thereof are preferably flared laterally as indicated at 9' so as not to present any sharp edges which would tend to cut or brade the sash rope. 80

Having thus described the invention, what is claimed as new is:

A sash weight comprising a hollow body threaded at one end, and a plug removably fitted to the said end of the body and closing 85 the same and having its upper side provided with an upstanding rectangular boss, the said plug being provided in its under side with a concavity and the plug being formed with an opening extending axially through 90 its top and axially through the boss, and the said boss being formed with a transverse opening intersecting and communicating with the first mentioned opening and opening through opposite sides of the said boss. 95

In testimony whereof we affix our signatures.

ALBERT B. CRESSLER. [L. S.]
LUDWIG B. NEES. [L. S.]
HARRY B. BAUMBACH. [L. S.]
